UNITED STATES PATENT OFFICE.

TORKILD VALDEMAR HEMMINGSEN, OF COPENHAGEN, DENMARK.

FUEL VALVE.

Application filed June 30, 1925, Serial No. 40,678, and in Denmark January 13, 1925.

This invention relates to a fuel valve for atomizing fuel by air pressure, such valve being applicable to Diesel motors in which the valve is to be placed horizontally or inclined downwardly or upwardly.

Referring now to the accompanying drawings:—

Figure 1 is a sectional elevation of a fuel valve according to my invention;

10 Figure 2 is a perspective view on a larger scale of a detail of Figure 1, and

Figure 3 is a side elevation of a modified constructional form of the detail shown in Figure 2.

15 According to the invention (Figures 1—3) a plurality of flat, angular or cup-shaped shelves *t* are arranged in front of the valve seat, reckoned in the direction of the air current. The inclination of the said shelves relatively to the inclination of the walls *s* from which they project, in the constructional form represented, the surface of a ring, corresponds to the inclination of the fuel valve relatively to a vertical plane. At 20 the inner end of each shelf the wall *s* is provided with holes *u*. The fuel oil is squirted on to the shelves and the compressed air in the valve casing *a* carries it through the holes *u* and eventually through known 25 atomizing rings *y* and an atomizing cone *z* to the compartment immediately in front of the valve seat *n* and from there through the atomizing ring *o* to the cylinder.

In order that the fuel oil may be squirted 30 on to the shelves *t* it is fed under pressure through a channel *p* of the atomizing tube *l*, in which the valve spindle *m* is movable, to an annular cavity *q* having a series of holes *r* along its periphery. The circle of 35 fuel oil jets squirted through these holes is then taken up by the shelves *t* of the ring *s*.

40 As some fuel oils will always run down from the shelves *t*, the atomizing tube *l* is at its lower side shaped as a cup *v* fitted tightly in the valve casing and provided only with a perforation *x* at its top through which the compressed air may pass from the valve casing *k* to the shelves *t* of the ring *s*. The cup *v* gathers the oil coming from the 45 shelves *t* and the oil gathered in the cup will be carried away successively with the compressed air. As already mentioned, one or more known atomizing rings *u* and a known atomizing cone *z* may be placed behind the special atomizing ring *s* with the shelves *t* in the direction of the air current.

A perspective view of the ring *s* is shown in Figure 2. The inclination of the shelves *t* relatively to the surface of the ring depends, as already stated, on the position in which the fuel valve has to work. When the shelves are flat, as shown in Figure 2, care must be taken that they are directed somewhat upwardly.

Figure 3 shows, in a modification, the atomizing ring *a'*, its shelves *b'* having an angular cross section so that the fuel oil will settle in the angle as shown at *c'*. The holes *u* correspond with the holes *u* of Figure 1 and the fuel oil projected on to the shelves *b'* is carried away from the latter through the holes *u* by the compressed air, the arrows *d'*, *e'* indicating the direction of movement. The oil may pass further through one or more atomizing rings of suitable form and the atomizing cone to the valve seat and finally into the cylinder.

The shape of the shelves *t* or *b'* may be varied in many ways; e. g. they may be cup-shaped. Care must only be taken that their shape and inclination is such that the fuel oil may rest for a while thereon.

I claim:

1. A fuel valve for use in a substantially nonvertical position, for internal combustion motors, comprising, a casing, atomizing rings in the casing, a plurality of shelves on one of the rings, projecting against the direction of flow through the casing with an inclination to the ring dependent upon the inclination of the fuel valve when in use, apertures in one of the rings adjacent and cooperating with, the shelves, a fuel inlet and an air inlet in the casing, and means for projecting fuel against the shelves. 95

2. A fuel valve for use in a substantially nonvertical position, for internal combustion motors, comprising, a casing, atomizing rings in the casing, a plurality of shelves on one of the rings, projecting against the direction of flow through the casing with an inclination to the ring dependent upon the inclination of the fuel valve when in use, apertures in one of the rings adjacent and cooperating with, the shelves, a fuel inlet and an air inlet in the casing, means for projecting fuel against the shelves, and an enclosing cup surrounding the shelves and apertured on its upper side. 105

3. A fuel valve for use in a substantially nonvertical position, for internal combustion motors, comprising, a casing, atomizing

rings in the casing, a plurality of shelves on one of the rings, projecting against the direction of flow through the casing with an inclination to the ring dependent upon the 5 inclination of the fuel valve when in use, apertures in one of the rings adjacent and cooperating with, the shelves, a fuel inlet and an air inlet in the casing, an enclosing cup surrounding the shelves and apertured 10 on its upper side, an annular chamber within in the cup, a passage connecting the annular chamber with the fuel inlet, and perforations in the wall of the annular chamber for permitting fuel to be projected against the 15 shelves.

4. A fuel valve for use in a substantially nonvertical position, for internal combustion motors, comprising, a casing, atomizing rings in the casing, a plurality of shelves 20 on one of the rings, projecting against the direction of flow through the casing with an inclination to the ring dependent upon the inclination of the fuel valve when in use, apertures in one of the rings adjacent and 25 cooperating with, the shelves, a fuel inlet and an air inlet in the casing, and means for projecting fuel against the shelves, the other atomizing rings being perforated and positioned beyond the said one ring considered 30 in the direction of flow, an outlet seat in the casing, and an atomizing cone between the outlet seat and the other atomizing rings.

5. A fuel valve for use in a substantially nonvertical position, for internal combustion 35 motors, comprising, a casing, atomizing rings in the casing, a plurality of shelves on one of the rings, projecting against the direction of flow through the casing with an inclination to the ring dependent upon 40 the inclination of the fuel valve when in use, apertures in one of the rings adjacent and cooperating with, the shelves, a fuel inlet and an air inlet in the casing, means for projecting fuel against the shelves and 45 an enclosing cup surrounding the shelves and

apertured on its upper side, the other atomizing rings being perforated and positioned beyond the said one ring considered in the direction of flow, an outlet seat in the casing, and an atomizing cone between the outlet 50 seat and the other atomizing rings.

6. A fuel valve for use in a substantially nonvertical position, for internal combustion motors, comprising, a casing, atomizing rings in the casing, a plurality of shelves 55 on one of the rings, projecting against the direction of flow through the casing with an inclination to the ring dependent upon the inclination of the fuel valve when in use, apertures in one of the rings adjacent and 60 cooperating with, the shelves, a fuel inlet and an air inlet in the casing, an enclosing cup surrounding the shelves and apertured on its upper side, an annular chamber within in the cup, a passage connecting the annular chamber with the fuel inlet, and perforations in the wall of the annular chamber for permitting fuel to be projected against the shelves, the other atomizing rings being perforated and positioned beyond the said one 65 ring considered in the direction of flow, an outlet seat in the casing, and an atomizing cone between the outlet seat and the other atomizing rings.

7. A fuel valve for use in a substantially 75 non-vertical position, for internal combustion motors, comprising, a casing, atomizing rings in the casing, a plurality of im- 80 perforate shelves on one of the rings, projecting against the direction of flow through the casing with an inclination to the ring dependent upon the inclination of the fuel valve when in use, apertures in one of the 85 rings adjacent and cooperating with, the shelves, a fuel inlet and an air inlet in the casing, and means for projecting fuel against the shelves.

In testimony whereof I affix my signature.

TORKILD VALDEMAR HEMMINGSEN.
